3 Claims. (Cl. 242—18)

The invention relates to a machine for the spooling of freshly spun synthetic filaments, which, after leaving the spinning nozzle, are wound untwisted into tapered windings.

In the spooling of freshly spun synthetic filaments, the spools and the winding build-up are largely determined by the spun material to be wound, on its delivery speed and the nature of further processing of the filaments. Diverse winding processes are being used, which endeavor to take account of these factors. In one manner or another, considerable improvements have been achieved. However, although spinning rates of the filaments could be increased without difficulty, these rates must be held back because the winding devices known today have about reached their maximum performance capabilities. Windings of untwisted, freshly spun filaments, which windings have tapered ends, are advantageous inasmuch as the filaments can be drawn off for further processing without forming a new winding prior to the processing.

In similar windings as, for example, in respooling or twisting, ordinarily a reciprocating system is used for the build-up on the spools of tapered windings. The yarn or filaments is deposited at a fixed or variable angle on the rotating spool by means of a traverse-motion thread guide. Machines for these windings operate under two basic principles, in which, during a winding operation, either only the reciprocating guide stroke applied to the yarn being wound is varied steadily or periodically and, for example, is brought from a maximum to a minimum or vice versa, or in which the yarn guide stroke field migrates constantly at a constant or variable stroke and, for example, is shifted alternately to the one and to the other side. Often both these types of distribution are combined.

Such a spool build-up either presupposes, however, a variable yarn delivery, which is adapted to the particular winding speed dependent on the traverse path and the spool circumference, or, conditions in constant delivery and constant or variable winding spool spindle turning speeds, special operations or means by which the differences in the winding speed, as, for example, in ring twisting, are compensated by means of variable runner speed. In the formation of spinning spools with tapered windings of freshly spun filaments, however, the application of these machines and winding principles runs into considerable difficulties, and, accordingly, there occur, during the winding build-up, differences in filament tension, which are brought about by the rapid change of wound layers or windings of smaller to larger diameters from the winding axis and vice versa or by changes of the distribution angle or with relatively long spool bodies and relatively large movement stroke of the filament guide (traverse triangle). These fluctuations in winding tension have an unfavorable effect on the spinning material and its structure, especially in this early stage of the development of the filaments, causing intolerable fluctuations in denier. The known devices, therefore, are unusable for practical purposes in the winding of delicate, freshly spun filaments, especially synthetic filaments of thermoplastic polymers, molten glass and the like. At best, because of the denier fluctuations which develop in large windings of these filaments, the known machines can spool only

2

windings of relatively small depth without substantial fluctuations in denier of the wound filaments.

Whereas otherwise in the spooling of yarns delivered at a constant speed, for the achievement of a constant or approximately constant circumferential velocity of the spool body regardless of winding diameter, drive drums are used, which turn at a constant speed and drive the spool body by friction. This principle cannot be applied for the spooling of delicate filaments without damage to the spun material. It has also been proposed that the speed of rotation of the spool be regulated in dependence on the growing winding in such a way that its take-up rate will always correspond to a constant delivery. The regulating devices provided for this purpose, which feel out the winding radius or the yarn tension by means of a member arranged as an impulse transmitter or in which the yarn as such is the impulse transmitter, act mechanically more or less strongly by contact pressure, yarn deflection or the like on the yarn and are incapable of satisfying higher demands required to maintain the quality of the filaments in the spooling of delicate spun material into spools with tapered ends directly after the filaments have been spun.

The delicate nature of the freshly spun filaments demands the winding of freshly spun, untwisted filaments in a free winding, i.e., without mechanical action on the winding or the filaments. The problem of free winding of spun material of delicate quality, accumulating at a high delivery speed, has to this day—despite the fact that there have been numerous proposals for its solution—not been satisfactorily solved. The core of the problem lies presumably largely in the fact that both in the formation of winding bodies with tapered ends by the known distributing or traverse systems and also merely as a result of the increasing circumferential velocity at the winding surface becoming greater with increasing winding diameter at constant turning speed of the spools, differences occur in the filament tension, which bring about undesirable fluctuations in denier.

In recognition of these relationships, it is proposed by this invention, that for the spooling of freshly spun synthetic filaments which, after leaving the spinning nozzle, are to be wound, untwisted, in free winding, into spools with tapered ends, that the filaments are supplied to the rotating spool in rapid traverse motion with constant, short, traverse strokes and are deposited in layers on the spool, which is moved axially back and forth with a stroke that is slower and longer than said short stroke and is continuously diminishing in length or diminishing in length in stages. In this arrangement, the speed of rotation of the spool is regulated in dependence on the stroke diminution of the axial movement of the spool, or the stroke diminution is regulated in dependence on the rate of revolution of the spool. The regulation of the revolution rate of the spool to maintain a substantially constant linear velocity of take-up of filament on the winding body preferably is done in response to the diminution of the axial spool stroke path. Where the stroke diminution operates in response to a decrease in rate of revolution of the spool, the regulation is controlled by a predetermined program. It is also possible to alter the speed of the stroke movement simultaneously in dependence on the stroke diminution of the axial spool movement.

In this manner an especially beneficial spin-spooling process is achieved, since neither filaments nor winding are acted upon by the control.

In the drawing:

FIG. 1 is a filament distribution diagram of the windings produced in accordance with the invention.

FIG. 2 is a perspective view of an embodiment of the invention for winding filaments into winding bodies with tapered ends;

FIG. 3 is an elevation of a spool with a filament winding body with tapered ends;

FIG. 4 is a schematic view, partly in section, of a known type of reciprocating drive for the spool carrier of the embodiment of FIG. 2; and

FIG. 5 is a schematic view of one type of electrical circuitry, of itself known, for changing the rate of rotation of the electric motor for the winding spindle by change of frequency of the current supplied to the motor.

As is schematically represented in the filament distribution diagram of FIG. 1, the distribution of the filaments on spools in winding bodies with tapered ends takes place in constantly or stepwise shorter, superposed layers or series of layers, of which each succeeding one is shorter than the preceding. Since the spool's rate of rotation is reduced to such a degree that its filament take-up rate corresponds to the delivery speed whereby filaments are wound at very nearly constant filament tension, the tension difficulties and denier fluctuations otherwise usual are avoided or reduced to a barely perceptible and tolerable amount. Moreover, in this manner even with filament delivery speed above that now used with known winding devices, windings with tapered ends of any desired volume can be formed with uniform filament quality.

For the execution of the process, a machine whose design and manner of operation is explained in detail is described and illustrated in FIGURE 2. The special features of this spooling machine for untwisted, freshly spun filaments are that the traverse device for the filaments is arranged to provide a regular, reciprocating, short stroke along the length of the winding spool or the winding thereon to the filaments just ahead of their delivery to the spool; the traverse or reciprocating mechanism for the spool or its carrier, on the other hand, is axially movable back and forth; and the control device for the shortening of the reciprocating stroke of the spool or its carrier is equipped with shifting means for the continuous or stepwise reduction of the spool rotation rate and, possibly, of the speed of the axial movement of the spool. Here, the reciprocating drive for the back-and-forth movement can be done by mechanical, hydraulic or pneumatic devices and the control for the rotation speed reduction or stroke speed of the spool can be made practicable by, among others, electrical means.

The winding machine comprises a spool or winding tube 1 removably mounted on a spool carrier or spindle 2. The drive shaft 3 for the spindle is rotatably journaled in bearing 4 and is driven by the drive motor 5. Both are mounted on the carrier slide 6, which is mounted on the guide rods 8 and 9, so as to slide along the rods. The guide rods 8 and 9 are mounted at each end thereof in rigid frame members, a segment 7 of the frame member being shown in FIG. 2.

The filament traverse mechanism 11 is driven by its own motor 10 at a predetermined, constant rate. It may be of any suitable construction which will reciprocate the filaments as they are wound on the spool 1. The mechanism shown in the drawing is a drum 12 with a continuous, curved slot 13 in its cylindrical side, through which slot the filaments F pass. As the drum 12 is rotated by the motor 10, the filament path is moved back and forth. Other means such as reciprocating stirrup can be used in place of the mechanism illustrated. The traverse mechanism may be mounted in a fixed position on a frame member 14 as shown in FIG. 2, or it may be mounted on a movable member such as pivot arm movable radially with respect to the spool axis.

The carrier slide 6 and winding mechanism mounted thereon is reciprocated by a piston rod 15 attached to the plate 16 which is mounted on the underside of the slide 6. The rod 15 is driven back and forth by a piston 17 in cylinder 18 of a hydraulic or pneumatic reverse drive 19. The opposite ends of cylinder 18 are con-

nected by conduits 22 and 21 for the hydraulic fluid or air with the hydraulic fluid or air tank 20.

The reverse drive 19 is connected with a control device which includes a threaded spindle 23, the threads 24 on one-half of the spindle being of an opposite hand to the threads 25 on the other half of the spindle. A movable block 26 is threaded on threads 24, and a movable block 27 is threaded on threads 25. The threaded spindle 23 is journaled in the two bearings 28 and 29 and is driven by electric motor 30 via a gear reduction box 31.

The blocks 26 and 27 are slidably mounted on a guide rod 32 extending between bearings 28 and 29 to prevent rotation of the blocks 26 and 27. When the spindle 23 is rotated by motor 30, the blocks 26 and 27 move in opposite directions on the threads 24 and 25 of opposite hand.

The blocks 26 and 27, respectively, carry switches 33 and 34. These switches are operated by the actuator 35 and are connected in an electrical circuit for transmitting direction control impulses to the hydraulic or pneumatic reverse drive 19.

Switches 36, 37 and 38 are adjustably positioned on the supporting frame 39. They are operated by the blocks 26 and/or 27 and operate in an electrical circuit of the motor 5 to diminish its rate of rotation, e.g., by changing the frequency of the drive motor 5. The switches 36-38 can also be used for the control of the stroke speed of the reverse drive 19 by acting on the pump output or special valves and thus changing the velocity of reciprocation of the carrier slide 6. While the illustrated embodiment shows three switches 36-38, all operated by contact with the bottom of the block 26, more than three switches may be used and operated by blocks 26 and/or 27 in a more frequent sequence to provide a more frequent sequence in the stepwise reduction of the rotation rate of the motor 5 to maintain a nearly constant linear take-up velocity of the filaments F into the winding on the spool 1.

The novel mode of operation of the spooling machine results from its special arrangement. The filaments F, delivered from a spinning nozzle at a constant velocity, usually are a multiple number of individual filaments. They are conducted back and forth by the traverse device 11 rotating at a constant turning speed to provide a constant short stroke across a fixed area and in this manner are deposited on the spool 1. In the process, the spool 1 with the components 2, 3, 4, 5, 6 carrying and driving it is moved back and forth by means of the piston rod 15 in rhythm of the piston movement of the hydraulic or pneumatic reverse drive 19 with a relatively great stroke gradually diminishing over the winding process.

As the winding operation begins, the motor 30 is energized, and it drives the spindle in a direction of rotation so that the blocks 26 and 27 slowly move toward the center of the spindle. The reversal of the direction of movement of the carrier slide 6 is effected by the operation of switches 33 and 34 on the slowly converging blocks 26 and 27 by the actuator 35. Each back or forth movement of the spool becomes shorter due to the converging of switches 33 and 34 on blocks 26 and 27.

By superimposition of the short, constant, rapid reciprocation of the filaments F by the traverse device 11 on the slower, diminishing stroke of the spool 1 relative to the filaments F, a layer of windings is built up on the spool, in which process each successive layer is shorter in length than the preceding layer. The respective layers of shortening length may be winding layers which are a single filament in depth or which are several windings in depth. This depends upon whether the relative rates of reciprocation of the filaments F by the traverse device 11 with respect to the reciprocation rate of the spool 1, at a given filament take-up velocity, is sufficiently high so that the filaments, under rapid reciprocation by the traverse device 11, build up a winding more than one filament in depth as the spool moves past the device 11 in a given direction.

Simultaneously, the circumferential velocity or speed of the winding on the spool is diminished to the degree which corresponds to the constant delivery speed of the filaments. For this purpose, the blocks 26 and/or 27 operate switches 36-38, and possibly additional switches, in a timed sequence corresponding to the times at which successive winding layers of greater diameter than the preceding winding layer begin to form, i.e., when the spool stroke reverses, to reduce the speed of motor 5.

In the drive unit of the threaded spindle 23, a mechanism of any suitable construction can be provided which drives the threaded spindle in reverse direction at a higher speed until the blocks 26 and 27 have been restored to their starting position while the wound spool is being replaced by an empty spool.

A spool wound by the process and machine of the invention is shown in FIG. 3 wherein the winding 40 on the spool or winding tube 1 is wound in a plurality of successive winding layers of diminishing lengths to give a winding with tapered ends 41 and 42. Even very delicate filaments can be wound into windings with tapered ends, even of relatively great volume of the winding, by the process of the invention wherein the winding speed is adjusted to remain substantially constant with the constant filament delivery in such a way that any fluctuations in denier remain within the desired narrow limits. A further advantage of the filament distribution on the windings according to the invention is that the crossing angle of the individual filament windings crossing in opposite direction alternates from layer to layer, whereby, as is well known, the winding build-up as such is improved and subsequent operations with the wound filaments are facilitated.

FIG. 4 shows the details of the reciprocating drive 19 for the carrier slide, 6, which is reciprocated by piston rod 15 connected to piston 17 in cylinder 18. This drive is shown in Patent No. 2,529,777, issued to W. H. McInnis on November 14, 1950. The piston is moved by hydraulic or pneumatic pressure delivered through control valve 45 consisting of a hollow cylinder having a rod 47 passing concentrically through the axial passage 46 and end plates 48 and 49 of the valve 45. Two pistons 50 and 51 are fixed on the rod 47 in spaced relation. The rod 47 is motivated by solenoids 52 and 53 on each end thereof. The energization of either of the solenoid coils moves the rod 47 and pistons 50 and 51 in one axial direction. Intake and outlet ports are provided in the valve. The central pipe 21 has connection with the intake port through which the fluid enters the valve, and oppositely disposed thereto are two pipes 54 and 55, which conduct the fluid to and from the cylinder 18. These pipes connect to opposite ends of the cylinder and become alternately intake and outlet, depending on the direction of travel of the piston. Two outlet pipes 56 and 57 are connected to opposite ends of the valve and lead to a common outlet pipe 22. Pipes 21 and 22 are connected to the fluid tank 20.

The switches 33 and 34 are operated upon contact by the actuator 35. When switch 33 is closed by the actuator, the solenoid 52 is energized, whereupon the piston rod 47 and pistons 50 and 51 move to the left as viewed in FIG. 4. In this position, piston 17 and rod 15 are moved toward the right. When actuator 35 closes switch 34, the rod 47 and pistons 50 and 51 move to the illustrated position, whereupon the direction of movement of piston 17 and rod 15 is reversed. This cycle is repeated throughout the winding operation.

FIG. 5 of the drawing is a schematic representation of the circuitry, in itself known, for variable speed motor 5. This circuitry involves the supply of current of different frequencies to the motor 5 under the control of switches 36, 37 and 38. The circuitry for supplying currents of

different frequencies to a work motor is that illustrated on page 104 (FIG. 73) of the text, "Electrobetrieb in der Textilindustrie," by Dr. Ing. W. Stiel, Verlag S. Hirzel, Leipzig (1930). In the illustrated case, currents of frequencies of 50, 75 and 100 cycles per second are generated in conductors 60, 61 and 62, respectively, by a 4-pole motor 63 driven by the 50 cycle current constituting the power supply. Motor 63 drives the 75 cycle, 4-pole generator 64 and the 100 cycle, 2-pole generator 65. The generators 64 and 65 supply their respective frequencies to the conductors 61 and 62.

Each of the frequency conductors is tapped by conductors 68, 69 and 70, which in turn are connected to poles or contact points of a switch 71 through which current at a given frequency is supplied to motor 5. The switch 71 is activated by a relay 72, e.g., the well known stepping relay, which operates in stepped sequence upon successive closing of switches 36, 37 and 38.

The invention is hereby claimed as follows:

1. A winding machine for winding freshly spun filaments into a winding body with tapered ends comprising a spindle adapted to hold a winding tube, power-operated means for reciprocating said spindle in an axial direction at a variable stroke length, drive means for rotatably driving said spindle at variable rates of rotation, filament feed means for reciprocating said filaments over a constant, short stroke length as they are fed to the winding tube on said spindle, a pair of control blocks, power-driven means for moving said blocks toward each other during the winding operation, a switch on each of said control blocks, switch-actuating means reciprocating with said power-operated means for actuating each switch during reciprocal movement of said switch-actuating means, control means operatively connected with each switch for reversing the direction of movement of said spindle by said power-operated means when said switch-actuating means actuates alternately each of said switches, additional switches sequentially operated by at least one of said blocks during movement thereof toward each other, and means operatively connected with said additional switches and said drive means to decrease the rate of rotation of said spindle by said drive means in a predetermined control program to maintain the filament velocity at the point of winding substantially constant during the winding operation.

2. A winding machine as claimed in claim 1 wherein said power driven means comprises a rotatably-driven screw with threads of opposite hand thereon, one of said blocks being threadedly mounted on a thread of one hand and the other of said blocks being mounted on a thread of the opposite hand whereby, upon rotation of said screw, said blocks may be moved toward each other during the winding operation, and motor-driven means for rotatably driving said screw.

3. A winding machine as claimed in claim 1 wherein said additional switches are mounted on a frame adjacent to and extending parallel with said rotatably-driven screw, said additional switches being adjustably spaced on said frame in the line of movement of at least one of said blocks whereby said switches are sequentially actuated by said at least one of said control blocks as said blocks move toward each other during said winding operation.
